UNITED STATES PATENT OFFICE.

WILLIAM YAPP, OF CLEVELAND, OHIO.

IMPROVEMENT IN TINSMITH'S FIRE-POTS.

Specification forming part of Letters Patent No. 39,521, dated August 11, 1863.

To all whom it may concern:

Be it known that I, WILLIAM YAPP, of the city of Cleveland, in the county of Cuyahoga and State of Ohio, have invented a new and improved tinsmith's fire-pot for heating and protecting the soldering-copper from smoke or sulphur or other injuries to the same caused by the surrounding fire; and I do hereby declare that the following is a full, clear, and exact description thereof, reference being had to the accompanying drawings, and to the letters of reference marked thereon, making a part of this specification, in which—

Figure 1 is a perspective view of the fire-pot. Fig. 2 is a front view. Fig. 3 is a side view. Fig. 4 is a vertical section through the fire-pot from side to side. Fig. 5 is a vertical section of the same from front to rear.

The nature of my invention consists in an improved combination and arrangement of parts whereby the heating of the soldering-coppers may be more readily and economically effected, the apparatus more easily supplied with fuel, its heat regulated and controlled, and means provided for placing the copper directly in the fire when it is to be forged to a point.

In order that others skilled in the art to which my invention appertains may be enabled to fully understand and use the same, I will proceed to describe its construction and operation.

A A represent horizontal cylinders, of which there may be one, two, or more, extending longitudinally through a rectangular box or casing, A, from end to end. Under these cylinders is placed the grate B, Figs. 4 and 5, leaving a space between the cylinders and the grate where the coal lies, as represented in Figs. 4 and 5. The coal is put into the fire-pot through an opening, C, Fig. 4, on the side, which is closed up again by a door, D, Figs. 1, 2, 3, and 4. In the top of the fire pot I leave an opening, F, Figs. 1, 4, and 5, provided with a collar, G, Figs. 1, 2, 3, 4, and 5, the same as is put onto any common stove to allow of a stove-pipe being put onto it for the escape of the smoke from the fire and to create a strong draft. I also provide the stove-pipe with a damper, such as are commonly used on ordinary stove-pipes to regulate the draft. By these means after the fire has been kindled a great heat can be obtained, and the

cylinders A thoroughly heated by opening a little the ash-box K. After the cylinders have become sufficiently heated the heat may be kept in the fire-pot by keeping the opening E, Fig. 5, closed by the door H, Figs. 1 and 2. Below the grate B is placed the ash-box K, made the same as in any ordinary stove. I also put the opening E, Fig. 5, in the front of the fire-pot, which can be kept closed by the sliding door H, Figs. 1 and 2, which will move in the slide-ways J, Figs. 1, 2, 3, and 5. The opening E is placed there to allow the soldering-copper to be put into the fire when necessary to forge it to a point. It will be clearly seen and understood that as the cylinders A are located in the center and pass entirely through the length of the fire-pot, the burning coal and the fire surrounding them must make the cylinders red-hot and consequently create an intense heat inside of them. In these cylinders now I place the soldering-copper L, as shown by Fig. 5, where it will be perfectly heated to use it for soldering.

The advantages gained by heating the soldering-copper in this manner are the following: The soldering-copper, not coming into contact with the fire itself, is kept free from smoke and sulphur caused by the burning of coal, which thus will not destroy the adhesive portion of solder, which must be on a soldering copper and which is commonly called the "face." This is a great saving of tools. The soldering-copper is also protected from getting overheated, which is also a reason for not destroying the adhesive portion of solder, whereas, on the other hand, when the soldering-copper is put into the fire itself, this adhesive portion will be destroyed when the same is getting overheated. Another advantage is also that, in this manner of heating the soldering-copper the same is always kept clean and ready for use. Furthermore, any kind of coal, whether anthracite or bituminous, may be burnt in this fire-pot. It is a well-established fact that this coal gives a greater heat and holds on longer than charcoal, which can only be used in the fire-pots at present in most common use. This is also a great saving of fuel, for a half bushel of hard or soft coal will burn longer and give more heat than one bushel of charcoal. In addition I wish to say that the fire-pot throughout is intended to be made of cast-iron, and that the cylinders can be made sepa-

rate and placed a small distance apart from each other. The cylinders can be taken out when burnt and be replaced by new ones.

By applying a register or door of any suitable form to the back of the furnace the rear ends of the tubes may be opened at will, to cause a circulation of air whenever it may be needful to cool the tubes, in consequence of their having become overheated.

I am aware that furnaces have before been devised for heating soldering-coppers within tubes, so as to protect them from direct contact with the fire, and therefore do not desire to be understood as claiming this invention, broadly; but,

Having thus described my invention, what I claim as new herein, and desire to secure by Letters Patent, is—

The combination, with the rectangular box or casing A', of one or more longitudinal cylinders, A, grate B, openings C E, doors D H, and sliding drawer K, all arranged as and for the purposes specified, and adapted for completely preventing circulation of air when required.

WILLIAM YAPP.
